(57) **CLAIM**

The ornamental design for a dog chew toy, as shown and described.

DESCRIPTION

FIG. 1 is a perspective view of a dog chew toy showing my new design;

FIG. 2 is another perspective view of the dog chew toy;

FIG. 3 is a front view of the dog chew toy;

FIG. 4 is a rear view of the dog chew toy;

FIG. 5 is a left-side view of the dog chew toy;

FIG. 6 is a right-side view of the dog chew toy;

FIG. 7 is a top view of the dog chew toy; and,

FIG. 8 is a bottom view of the dog chew toy.

The broken lines illustrate portions of the dog chew toy that form no part of the claimed design.
